UNITED STATES PATENT OFFICE.

WILLIAM T. CAMPBELL, OF NEW YORK, N. Y.

DESIGN FOR A SPRINKLER-TOP FOR BOTTLES.

46,722.

Specification for Design.

Patented Dec. 8, 1914.

Application filed October 6, 1914. Serial No. 865,384. Term of patent 3½ years.

To all whom it may concern:

Be it known that I, WILLIAM T. CAMPBELL, a citizen of the United States, and a resident of the city, county, and State of New York, have invented a new, original, and ornamental Design for a Sprinkler-Top for a Bottle, of which the following is a specification, reference being had to the accompanying drawings, forming a part hereof.

Figure 1 is a side elevation of the sprinkler-top embodying the design. Fig. 2 is a plan view thereof.

I claim:

The ornamental design for a sprinkler-top for a bottle, as shown.

WILLIAM T. CAMPBELL.
